UNITED STATES PATENT OFFICE

2,519,179

SINTERING MACHINE

William M. Duncan, Alton, Ill.

Application June 19, 1947, Serial No. 755,770

4 Claims. (Cl. 266—21)

1

This invention relates generally to apparatus for sintering ores and particularly to plural strand sintering machines, although some of the features of the invention will be applicable to single strand sintering machines.

In the treatment of ores, which require agglomeration, the sintering machine has long been a familiar piece of apparatus. It consists essentially of a series of pallets, each adapted to contain a bed of raw ore. The pallets are arranged to be moved about an endless path, at one extremity of which they are filled and at the other extremity of which they are emptied. While laden with the ore, and the added fuel which is necessary to increase the temperature, the succession of pallets traverses the mouths of a plurality of wind boxes whereby a draft is induced through the bed of material on the pallets.

The sintering machine as described above was originally a reasonably efficient and dependable apparatus for its intended purpose, but with the demand for increased production, more recent efforts to achieve additional capacity, by enlarging the pallets, have reached the point of diminishing return. Of late it has been proposed to construct such sintering machines with pallets having a length (i. e., width of the sintering machine) of ten feet or more so that the ore bed on each pallet would weigh many hundred pounds. With such an apparatus constructed along conventional lines it would be necessary to provide an endless path having a height on the order of fifteen feet with drive sprockets correspondingly proportioned. With a sintering machine of the magnitude just referred to and even with smaller machines, great difficulties are encountered in properly regulating and maintaining the uniformity of the induced draft of air through the ore-fuel bed with resultant lack of uniformity in the sintering of the ore being treated. Furthermore, with pallets of the magnitude referred to, it is practically impossible to control the driving force so as to avoid twists, tortions, and strains, which frequently will result in broken pallets and consequently loss of the ore bed carried thereon. All these factors would contribute toward a marked loss of efficiency and would result in aggravated difficulty in maintenance and in continuity of operations.

The object of the present invention, generally stated, is to provide a sintering apparatus having a high capacity without utilizing pallets of such proportions as to be impractical.

Another object of the invention is to provide a sintering machine wherein the pallets may be

2

expeditiously removed and replaced in their operative succession without interrupting the continuous operation of the machine.

A further object is to provide an improved drive for the pallets of the sintering machine, which will assure the movement of the pallets along their track without twisting and skewing.

Other objects will become apparent as the following description is read in connection with the accompanying drawings in which:

Figure 1 is a view in side elevation of a sintering machine constructed in accordance with the present invention;

Figure 2 is a sectional view taken along line 15 2—2 of Figure 1;

Figure 3 is an enlarged detail view of the drive sprocket for the sintering machine shown in Figure 1;

Figure 4 is a sectional view taken along line 20 4—4 of Figure 3;

Figure 5 is a sectional view showing in plan a pallet transfer mechanism constructed in accordance with the present invention;

Figure 6 is a view in side elevation of the pallet 25 transfer mechanism; and

Figure 7 is a sectional view taken along line 7—7 of Figure 6.

For economy of floor space, freedom from mechanical difficulties and assurance of uniform sintering of the ore bed, together with relatively 30 high capacity, the present invention contemplates, in general, that a sintering machine be provided with a plurality of strands of pallets so disposed with reference to each other as to operate in parallel, and otherwise so coordinated that the attention of one operative crew will suffice. A particular feature of the present invention resides in the arrangement of the wind boxes for the respective strands of pallets so as to be 35 individually controlled yet energizable by a common source and utilizing a single dust collector.

A further feature of the invention resides in the provision of a drive and interlocking connections with the several pallets of a character such 40 that radial displacement between the opposite ends of the pallets due to torsional twist of the drive shaft or due to wear of the interlocking connections is substantially prevented.

Referring now to Figures 1 and 2 of the drawings, a succession of pallets 1 is mounted upon a stationary endless track having an upper reach 2, which is substantially horizontal, and an inclined lower reach 3. The present invention contemplates that the pallets 1 be preferably not over 45 six feet long and not over twenty-four inches

wide. The pallets 1 are otherwise constructed in accordance with the usual practice having a grated bottom.

At the end portions, the endless track is preferably in the form of a channel, as shown clearly in Figure 4, so that flanges 4 and 5 lie respectively on the radially outward and radially inward sides of trunnions 6 which extend from each end of each pallet. The reaches 2 and 3, which intervene the end portions of the endless track, need not be provided with flanges both above and below the trunnions 6, it being sufficient, and in fact preferred, that along the reaches 2 and 3, the flanges of the track extend only beneath the trunnions 6.

In accordance with the usual practice, the trunnions 6 may be provided with rollers.

As in any such sintering machine, a feed bin 7 is mounted above the endless track for the pallets near one end thereof and is provided with a swinging spout 8 (of the conventional type) and a suitable control valve 9. As shown in Figure 2, where the sintering machine of the present invention consists of two separate strands of pallets, duplicate such feed bins and spouts are provided.

Adjacent the feed bin 7 a suitable ignition furnace 10 is provided for igniting the mixture of ore and fuel with which the respective pallets are laden.

Arranged below the upper reach of the track 2 and extending from a position directly beneath the ignition furnace 10 toward the discharge end of the machine is a plurality of wind boxes 11, each arranged in accordance with the usual practice to extend as close as practicable to the bottoms of the several pallets 1 as the latter traverse their endless path. The wind boxes 11 for the left hand strand of pallets (as seen in Figure 2) are duplicated by corresponding series of wind boxes 12 arranged for the right strand of pallets (as seen in Figure 2).

In order to conserve space and at the same time contribute toward the efficiency of dust separation from the gases exhausted through wind boxes 11 and 12, the present invention contemplates that the ducts connecting wind boxes 11 and 12 for the respective pallet strands be in the form of a Y. The branches 13 and 14 of the Y duct connect respectively with the wind boxes 11 and 12 and merge into a constricted vertical leg 15 which extends downwardly, between the two strands of pallets, and constitutes a unitary duct leading to a single dust collector 16 adapted to receive the output of both wind boxes 11 and 12. The arrangement just described has the further feature of accommodating the pallet transfer mechanism later to be described. In order to regulate the draft induced through the ore beds above the wind boxes 11 and 12, respectively, the branches 13 and 14 are each provided with suitable dampers 130 and 140. In this way ore beds differing in composition and/or characteristics may be concurrently treated on the respective strands.

As shown by the drawings, the dust collector 16 is energized by two vacuum systems 17 and 18, but it should be understood that one exhauster of appropriate capacity will suffice. The merging together of the dust laden gaseous output of wind boxes 11 and 12 and the constriction of the interflowed streams from such wind boxes respectively contributes toward the efficiency of dust recovery.

For driving the series of pallets about their

endless path a pair of sprockets 20 is provided for the left strand (as seen in Figure 2) and a corresponding pair of sprockets 21 for the right strand. The paired sprockets are mounted upon shafts 22 and 23 respectively suitably supported in appropriate bearings upon the framework of the sintering machine. Mounted centrally upon each of the shafts 22 and 23 is a drive gear 24 which engages a pinion 25 mounted upon a jack shaft 26. The jack shaft 26 is driven by a motor 27. While in the embodiment shown in the drawings the jack shaft 26 transmits the power from motor 27 to the driving gears 24 for both pairs of sprockets, it will be understood that, if desired, separate motor drives for each strand may be provided. Any suitable clutch for selectively engaging or disengaging the driving connection between motor 27 and shafts 22 or 23 is preferably provided. Such a clutch may, for example, involve mounting the gears 24 upon a spline so as to be slidable axially of their shafts 22 and 23, respectively, into positions whereat they will either engage with or be disengaged from the pinions 25. Alternatively, the clutch may involve a similar shift of the axial position of the pinions 25. Likewise, it is desirable to provide variable speed transmissions between the drive shaft and the driving pinions, thereby to control the lineal speed of one strand of pallets independently of the other where it is desirable to do so. Since clutch mechanisms and variable speed transmissions of the character required are well known in the art, the details thereof are not shown in the accompanying drawings.

The disposition of the drive gear 24 midway between the sprockets 20 or 21, as shown in the drawings, is of particular advantage in that any torsional twist to which the shaft 22 may be subject, because of the tangential load which is imposed on the sprockets, is equally distributed on both sides of the drive gear 24. Consequently, if such torsional twist should attain a magnitude such that either of the sprockets 20 lags behind its normal unstrained position relative to gear 24, both sprockets will lag to the same degree. Such an arrangement therefore eliminates the troublesome cocking of the pallets on their track, which has heretofore been experienced with drives which were powered from one end only.

In order to further reduce the tendency of the pallets to cock in their track and to facilitate the movement of the pallets about the turns in the endless track, the present invention contemplates that each of the sprockets be provided with roller teeth in lieu of the usual integral teeth. Consequently, in the embodiment shown, the sprockets 20 and 21 are provided about their periphery with a series of rollers 28 mounted upon shafts 29, which latter are supported between spaced legs 30 preferably cast integral with the sprocket 20, in the radial positions of the usual sprocket teeth. The rollers 28 are circumferentially spaced to correspond with the spacing of trunnions 6 on each of the pallets, which is to say that the inter-axial spacing between two successive rollers 28 is the same as the inter-axial spacing between two successive trunnions 6, whether the latter are on the same or different pallets. It is preferable, however, that the rollers 28 be selected of a diameter slightly less than the linear distance between the proximate peripheries of succeeding trunnions 6. Otherwise, when there is rolling movement between a given roller 28 and a trunnion 6 immediately

ahead of it, there might be sliding movement between said roller and the trunnion engaging the same on the other side.

At the discharge end of the sintering machine, a curved track 31 is provided for directing the pallets from the upper reach 2 to the lower reach 3.

In order to facilitate the removal and replacement of pallets having burned out grate bars, without interrupting the operation of the sintering machine, the present invention contemplates the provision of a lift and transfer mechanism between the upper and lower reaches of the endless path for the pallets. The arrangement of the lift and transfer mechanism in this manner is made possible by the novel arrangement of the wind boxes and ducts as described above. In the space which, in accordance with the prior practice, has been occupied by the ducts leading from the wind boxes the present invention contemplates the provision of an over-head rail or trolley 32, which is mounted so as to extend substantially horizontally between the upper and lower reaches of the pallet series. For a substantial distance between the upper and lower reaches of the pallet series, the trolley 32 extends in a direction parallel to the length of the sintering machine, but toward the drive sprockets 20 the trolley curves, as shown clearly in Figure 5, so as to extend to the exterior of the sintering machine.

Mounted upon the trolley 32 is a pair of dual hoists 33 and 34. The hoists 33 and 34 may be identical and each is preferably provided with two lifting mechanisms interlocked so as to operate together. For example, in the embodiment shown, the mechanisms are compressed-air-operated and the hoist 33 is provided with two air cylinders 35 and 36, one on each side of the trolley 32. Likewise, the hoist 34 is provided with two air cylinders 37 and 38, one on each side of the trolley 32. Cylinders 35 and 37 work together but entirely separate from cylinders 36 and 38, which latter work together.

In the embodiment shown, the two pairs of dual hoists are inter-connected to provide a unitary transfer mechanism, which is mounted upon wheels 39 entracked upon trolley 32.

With such an apparatus the removal and replacement of a pallet from the series may be accomplished with facility and speed. From outwardly beyond the confines of the sintering machine, the transfer mechanism may be moved with hoist 34 laden with a new pallet 40 suspended upside-down ready to be dropped into position in the series of pallets when one is removed. When the transfer mechanism is moved to the interior of the sintering machine, bearing a new pallet 40 as just described, it is contemplated that the hoist 33 be unloaded. When the pallet which it is desired to remove from the machine reaches a position beneath the hoist 33, said pallet is engaged by the hoist, lifted out of position in the series, and then, while the removed pallet is still suspended by hoist 33, hoist 34 is lowered to deposit pallet 40 in position in the series.

Between the operation of the two hoists 33 and 34, as just described, sufficient time may elapse that one or more pallets have passed the locus of operation so that the new pallet may not be in the exact position relative to the other pallets as was the removed pallet, but such is immaterial.

In order to retard the movement of the succession of pallets past the locus at which the

interchange just described is being made, the invention further contemplates the provision of a brake 41 having a shoe 42 adapted to frictionally engage the bottom surface of the pallets as they traverse a position immediately in advance of the locus at which the interchange is being made. The brake 41 is not a positive brake, which would require interruption of the machine, but is preferably an impositive brake which, while retarding the movement of pallets along the lower reach of the machine, will, none the less, permit the machine to continue in operation. In the embodiment shown in the drawings, the brake 41 is provided with a spring 43 tending to hold shoe 42 in engagement with the pallets. The spring 43 operates through a lever 44 secured as a crank upon a shaft 45. The shaft 45 is also provided with a gear 46 driven by a pinion 47 from a crank 48 so as to facilitate the movement of lever 44 from the position shown in Figure 6 to an opposite position whereat the tension of spring 43 will tend to rotate lever 44 in the opposite sense. Upon the extremity of shaft 45, an eccentric 49 is provided and upon said eccentric the brake shoe 42 is carried. With such an organization of parts, it is apparent that, when the parts are in the position shown in Figure 6, the spring 43 tends to move the shoe 42 so as to grip and retard the movement of the pallets, but, under normal operating conditions, the parts will assume a position wherein lever 44 extends in a nearly opposite direction to that shown in the drawings. In the latter position the tension of spring 43 will tend to maintain the shoe 42 out of engagement with the pallets. While the brake 41 is primarily intended for retarding the movement of the pallets along the inclined lower reach of their path during interchange, such a brake may none the less be continuously employed, and in fact a plurality thereof may be provided along the lower reach of the pallet path, so as to retard the movement of the pallets thereon, especially when the path may be incompletely filled with pallets.

With the transfer mechanism of the character above described, a replacement pallet may be moved into position and the pallet, being replaced, taken from the sintering machine and deposited beyond the confines thereof with but one maneuver of the transfer mechanism along its track 32, it being understood that, somewhere in a convenient location beyond the confines of the sintering machine, there will exist a supply of replacement pallets and a point for disposing of the pallets to be reconditioned, both of which will be served by trolley 32.

In order that the hoists 33 and 34 may readily engage the pallets, the hoists are provided with a set of toggle hooks 53 and 54, the upper ends of which are pivoted on a collar 55, which is slidably mounted on the rod extending from the piston within each of cylinders 35-36 and 37-38, as the case may be. The lower end of the piston rod is secured to a head 56. A pair of links 57 extend between head 56 and toggle hooks 54. The toggle hooks 54 have their lower extremities proportioned to pass between the bars which constitute the grated bottom of the several pallets and engaged projections therein located, it being understood that during the transfer operation the pallets are upside-down.

A further feature of the present invention involves the provision of a hood 58 adjacent the discharge end of the sintering machine and embracing the last wind box of the series 11 as well as a negative wind box 51. The terminal wind

box 51 may be identical in structure with the other wind boxes of the series 11. Save that the flow of gas through the box 51 is opposite in direction to the flow of air through the series 11, wind box 51 is preferably provided with a suitable blower for drawing cool air from the atmosphere and forcing the same upwardly through wind box 51. Flue gas flows downwardly through boxes 11 while cool air flows upwardly through box 51. Consequently, the flow of air through the pallets above wind box 51 is in an upward direction as distinguished from the down flow of air through the pallets above the wind boxes 11. Such a reversal of the flow of air through the ore bed on the pallets for a brief interval contributes to the efficiency of the sintering operation particularly as concerns particles of fuel or ore which may have been baffled (due to their peculiar disposition in the bed) against air flowing in the opposite direction. Hood 50 directs the air (which has been preheated by passing upwardly through the pallets above windbox 51) into the last wind box of the series 11, thus facilitating combustion of the last vestige of fuel remaining in the bed. Moreover, such reversal of the flow of air through the sinter bed has an important cooling effect upon the hottest part of the sinter, which is deep in the bed, thus sufficiently hardening the semi-plastic sinter that it will slide freely from the grate bars.

From the foregoing description, those skilled in the art should readily understand that the invention accomplishes its objects and that, by the provision of a plural strand sintering machine, numerous mechanical and operational advantages are attainable. While the various features of the machine have been described with particular reference to plural strand sintering machines, it should be understood that many of such features are applicable to single strand machines and it is therefore to be distinctly understood that certain aspects of the invention are not limited to plural strand sintering machines.

While one complete embodiment has been disclosed in detail, various modifications and alterations will immediately suggest themselves to those skilled in the art and it is therefore to be distinctly understood that such modifications and variations as do not depart from the spirit of the invention are, although not specifically described herein, contemplated by and within the scope of the appended claims.

Having thus described the invention, what is claimed and desired to be secured by Letters Patent is:

1. In an apparatus for sintering ores, a plurality of series of pallets mounted on endless tracks, each series having separate parallel closely adjacent tracks, separate wind boxes below the upper reaches of each of said tracks respectively, exhaust means adapted to pull air through pallets disposed above the wind boxes respectively, a dust collector, and a unitary duct connected to both said wind boxes and extending to said dust collector.

2. In an apparatus for sintering ores, a plurality of series of pallets mounted on endless tracks, each series having separate parallel closely adjacent tracks, separate wind boxes below the upper reaches of each of said tracks respectively, exhaust means adapted to pull air through pallets disposed above the wind boxes respectively, a dust collector, and a Y-duct extending from said separate wind boxes to said dust collector, the leg of said Y-duct extending vertically between the respective wind boxes.

3. In an apparatus for sintering ores, a plurality of series of pallets mounted on endless tracks, each series having separate parallel closely adjacent tracks, separate wind boxes below the upper reaches of each of said tracks respectively, exhaust means adapted to pull air through pallets disposed above the wind boxes respectively, a dust collector, a unitary duct connected to both said wind boxes and extending to said dust collector, each of said series having one wind box free of direct connection with said dust collector, and a hood overlying said last mentioned wind box and the next adjacent wind box for substantially limiting the air drawn through said next adjacent wind box to air which has been preheated by having first traversed pallets above said one wind box, said one wind box being positioned under said hood at the side toward the discharge end of said endless track.

4. In an apparatus for sintering ores having a series of pallets mounted for movement about an endless track; a succession of wind boxes opening in close adjacency to and beneath the series of pallets, means for drawing air downwardly through said wind boxes, a final similarly disposed wind box unconnected with said means but vented to the atmosphere below the pallets, and a hood embracing the pallets above said final wind box and the next adjacent wind box to limit the flow of air through the pallets above said adjacent wind box to that which has been preheated by passing upwardly through the pallets above said final wind box.

WILLIAM M. DUNCAN.
